UNITED STATES PATENT OFFICE

158,183

BOTTLE CARRIER

John F. Eder and George H. Wilcox,
Sherman, Tex.

Application March 18, 1949, Serial No. 1,452

Term of patent 14 years

(Cl. D58—4)

To all whom it may concern:

Be it known that we, John F. Eder and George H. Wilcox, citizens of the United States, residing at Sherman, in the county of Grayson and State of Texas, have invented a new, original, and ornamental Design for a Bottle Carrier, of which the following is a specification, reference being had to the accompanying drawings, forming a part thereof.

Figure 1 is a perspective view of a bottle carrier, showing our new design;

Figure 2 is a bottom plan view of the same.

We claim:

The ornamental design for a bottle carrier, as shown.

JOHN F. EDER.
GEORGE H. WILCOX.
